UNITED STATES PATENT OFFICE.

HYMAN UFFNER, OF NEW YORK, N. Y.

CONTAINER.

1,108,281.

Specification of Letters Patent. Patented Aug. 25, 1914.

Application filed April 2, 1914. Serial No. 329,004.

To all whom it may concern:

Be it known that I, HYMAN UFFNER, a citizen of the United States, residing at Brooklyn, county of Kings, city and State of New York, have invented certain new and useful Improvements in Improved Containers, of which the following is a clear, full, and exact description.

This invention relates to improved containers for various articles, particularly adapted to contain flat phonograph records.

The object of the invention is to provide a simple, durable and efficient device of the kind which will permit access to the records more readily than in the present albums employed for that purpose.

A further object is to secure the result desired by use of as little cabinet room as possible.

In carrying out my invention, I provide either a single box or a cabinet of boxes or partitions, which I term "inclosing members" for containing the box or drawer which is to contain the records, and which I term the "containing member." A cam and cam slot and guard plate secure the two members together, and permit the containing member to be drawn horizontally out for a distance, and then swung on an arc outside of the inclosing member so that the containing member will have its front part drop below the inclosing member; thus I am enabled to secure the swinging of the containing member without providing for any increased height in the cabinet.

The scope of my invention will be pointed out in the claims.

In the accompanying drawings: Figure 1 is a side elevation partly open of one unit of my improved device. Fig. 2 is a side elevation, opposite side of Fig. 1, with the device in closed position. Fig. 3 is a view similar to Fig. 2 with the device in open position. Fig. 4 is a section on line 4—4 of Fig. 2. Fig. 5 is a section of a cabinet provided with a number of my units.

As shown in the drawings, 1 is the inclosing member, which consists of an ordinary box-like structure having an open front with a cam slot 2 in the wall thereof, but covered with the material which covers the box if it be a unit. If it be made with compartments as shown in Fig. 5, the covering will of course be omitted. To the wall of the member 1, adjacent to the cam slot, I locate and secure by rivets or otherwise a

guard plate 3 having an aperture 4 conforming in shape to the cam slot, which receives the stem 5 of a stud which carries an enlarged head 6 within the cam slot. 60 The stud is secured by washers 7 and 8 to the wall 9 of the containing member 10.

The containing member is constructed with an ordinary closed front 11 provided with a grasping ring 12 and preferably 65 with one complete side 13, that is, complete excepting that the upper inner corner is made in the form of an arc to permit a pivoting of the device when it is in the position of Fig. 3. The opposite side 14 I prefer 70 to make of approximately half the height of the box, exposing from that side the envelope 15 and the records 16. The back wall of the box 17 I extend preferably only up so far as to meet the top of the side 14. 75

In carrying out this invention, details of construction may be varied from those shown, and yet the essence of the invention be retained; some parts might be employed without others, and new features thereof 80 might be combined with elements old in the art in diverse ways, although the herein described type is regarded as embodying substantial improvements over such modifications. 85

As many changes could be made in the above construction, and many apparently widely different embodiments of the invention could be made without departing from the scope thereof, it is intended that all 90 matter contained in the above description or shown in the accompanying drawings shall be interpreted in an illustrative and not in a limiting sense.

It is furthermore desired to be understood 95 that the language used in the following claims is intended to cover all the generic and specific features of the invention herein described, and all statements of the scope of the invention which as a matter of language 100 might be said to fall therebetween.

I claim as my invention:

1. The herein described container for phonograph blanks and the like, consisting of the inclosing receptacle, the containing receptacle adapted to fit within the inclosing receptacle, and a cam mechanism securing the two together but adapted to permit the withdrawal of the containing receptacle from the inclosing receptacle for a limited 110 distance, and then permit a pivoting of the containing receptacle.

2. The herein described container for phonograph blanks and the like, consisting of the inclosing receptacle, the containing receptacle adapted to fit within the inclosing receptacle, and a cam mechanism securing the two together but adapted to permit the withdrawal of the containing receptacle from the inclosing receptacle for a limited distance, and then permit a pivoting of the containing receptacle, the containing receptacle having its inner and upper edges of less height and length than its outer and lower sides respectively.
3. The herein described container for phonograph blanks, and the like, consisting of the inclosing receptacle, the containing receptacle adapted to fit within the inclosing receptacle, and a cam mechanism securing the two together, but adapted to permit the withdrawal of the containing receptacle from the inclosing receptacle for a limited distance, and then permit a pivoting of the containing receptacle, said cam mechanism consisting of a cam slot in the wall of the inclosing member and a pin retaining the containing member at all times in movable but permanent relation to the inclosing member.
4. The herein described device consisting of the inclosing member having a cam slot and guard plate, a headed stud, the head 3 within the cam slot, the stem of the stud projecting through the guard plate, a containing member, the side of which is secured to said stud.
5. The herein described device consisting 35 of the inclosing member having a cam slot and guard plate, a headed stud, the head within the cam slot, the stem of the stud projecting through the guard plate, a containing member, the side of which is secured 40 to said stud, the containing member of rectangular shape, with the upper inner corner cut away whereby it may be slid and guided horizontally for part of its distance, and permitted to rock during the rest of its motion.

Signed at New York city, in the county of New York and State of New York, this 1st day of April, 1914.

HYMAN UFFNER.
